UNITED STATES PATENT OFFICE

SAMUEL E. SPERRY, OF HOLLIS, NEW YORK, ASSIGNOR TO INTERTYPE CORPORATION,
OF NEW YORK, N. Y., A CORPORATION OF NEW YORK

SHIFTING MEANS FOR MATRIX MAGAZINES

Application filed June 5, 1928. Serial No. 283,057.

The present invention relates to improvements in typographical machines of the general class shown and described in Letters Patent No. 436,532 granted September 16, 1890 to O. Mergenthaler wherein matrices are delivered from a magazine, by the operation of a keyboard, to a point where they are assembled in a line after which the line is transferred to a point where a type bar or 10 slug is cast therefrom, and it relates more especially to machines of this class which are constructed to contain a plurality of matrix magazines for matrices of different fonts, the magazines being shiftable so that one or another thereof may be brought into position to deliver matrices therefrom under the control of the keyboard, as may be required.

Plural magazine machines of this class as heretofore built have usually employed mechanism for moving the lower ends of the magazines through arcuate paths in order to enable the escapements on the lower ends of the magazines which control the delivery of the matrices therefrom to pass over or clear the 25 escapement actuating rods or reeds of the keyboard, but the mechanism required has been complicated and the magazine shifting operations to be performed by the operator have been awkward, difficult and laborious. In Letters Patent No. 1,229,160 granted to me on June 5, 1917, is shown and described simplified means whereby the magazines may be shifted to bring one or another thereof into use by moving them in a substantially 35 straight line forwardly or rearwardly, but in order to accomplish this, means are required for lowering the keyboard reeds out of the path of the lower ends of the magazines, and such a construction presents the 40 disadvantage that it requires the use of a set of short or supplemental reeds above the main reeds and which must be shifted out of operative position between the upper ends of the main reeds and the magazine escapements prior to each shift of the magazines 45 and must be returned to such operative position after each shift has been made.

The primary object of the present invention is to provide novel and improved magazine mounting and shifting means therefor

wherein the construction is simplified and the magazine shifting operations may be performed with greater speed and facility by the operator while he occupies his usual seat at the keyboard of the machine, the invention 55 embodying means for tipping upwardly the lower or forward ends of the magazines so that they will clear the upper ends of the escapement actuating reeds, which may be of the usual construction, and means for shifting the magazines either forwardly or rearwardly 60 in a substantially straight line while the magazines are so tipped, thus bringing the desired magazine into position for use, the operating handles or other means for tipping and shifting the magazines being within convenient reach of the operator while he occupies his usual position at the keyboard of the machine.

Another object of the invention is to provide means which is operative automatically by the means which tips the magazines for swinging the channel entrance which serves to direct the returning matrices from the distributor to the magazines out of its normal 70 position between the distributor and the upper end of the magazine in use, when the upper ends of the magazines are tipped upwardly, thereby removing the channel entrance from a position where it would otherwise obstruct the shifting movements of the magazines and for returning the channel entrance to its normal operative position between the distributor and the upper end of such magazine as has been brought into use 75 when the forward ends of the magazines are lowered to bring the escapements on the selected magazine into working relation with the keyboard reeds on the stationary main frames.

A further object of the invention is to so mount and balance the magazine structure as to enable it to be shifted with minimum effort, thus enabling the operator to shift the magazines as may be desired while seated at the 95 keyboard of the machine.

To these and other ends, the invention consists in certain improvements and combinations and arrangements of parts all as will be hereinafter more fully described, the features 100

of novelty being pointed out particularly in the claims at the end of the specification.

In the accompanying drawings:—

Fig. 1 is a front elevation of the upper portion of a typographical machine of the class hereinbefore referred to, the view being partly in section and showing magazine mounting and shifting means embodying the present invention;

Fig. 2 is an elevation of the structure shown in Fig. 1 as viewed from the right hand side thereof, one of the magazines and the cooperating channel entrance being shown in operative position;

Fig. 3 is a view similar to Fig. 2 but showing the upper ends of the magazines tipped upwardly and the channel entrance swung rearwardly to clear the upper ends of the magazines, the full lines showing the magazine unit in its foremost position and the dotted lines representing another position into which the magazine unit may be shifted to bring another magazine into use.

Fig. 4 is a side elevation of the magazine unit shown in the preceding figures but detached from the machine; and

Fig. 5 is a view similar to Fig. 2 but showing different means for mounting the upper portion of the magazine on the main frame of the machine.

Similar parts are designated by the same reference characters in all of the figures.

The present invention is applicable generally to typographical machines wherein a plurality of magazines are superposed to form a stack and the magazines occupy a downwardly and forwardly inclined position on the machine so that the matrices introduced into the upper end of the magazine from the distributor will slide downwardly therein by gravity and the matrices will discharge from the lower end of the magazine by gravity under control of escapements usually carried by the lower end of each magazine, the escapements being actuated by reeds or equivalent rods which are mounted in the stationary main frame of the machine and are pushed upwardly under the control of a keyboard so that they actuate the respective escapements on a magazine in operative position. The preferred constructions are shown in the accompanying drawings and will be hereinafter described in detail but it is to be understood that the invention is not restricted to the precise constructions shown as equivalent constructions may be used and such will be included within the scope of the claims.

In the present instance, 1 represents a portion of the main stationary frame of the machine, 2 represents the distributor which as is well known receives the matrices used in a line from which a cast has been made and returns the matrices to the magazine, 3 represents the channel entrance which may be similar to the channel entrance usually used

in machines of this class to guide or direct the matrices dropping from the distributor into the upper ends of the respective channels of the magazines and 4 represents the escapement actuating reeds which are reciprocated vertically in the relatively stationary forward portion 1^a of the main frame under the control of a keyboard which may be of the usual well known construction and located at the front of the machine for manipulation by the operator.

The magazine mounting and shifting means according to the present invention is applicable to two, three or more matrix magazines, three of such magazines designated 5, 6 and 7 being shown in the present instance, and these magazines are preferably mounted in a single unit frame 8 which may be similar to the magazine carrying frame shown in my prior patent above referred to, the magazines being so mounted in the frame that they may be individually removable therefrom to enable the magazines to be changed if desired. In the construction shown in Figs. 1 to 4 inclusive, the frame 8 has supporting tracks 9 and 10 fixed to or formed as parts thereof, and the two upper magazines rest removably on the respective frames 5^b and 6^b, these frames having lugs 5^c and 6^c which extend outwardly and downwardly from their edges, the lugs 5^c resting on and being secured as for example, by screws, to the lugs 6^c, while the lowermost magazine 7 rests removably on the frame unit 8 and the latter has lugs 8^c thereon on which the lugs 6^c rest and to which they are secured as for example by screws.

It will be understood however that the magazine shifting means embodying the present invention is applicable to other magazine supporting frame structures such for example as one wherein each magazine is mounted on a separate flat frame and the flat frames are secured to the tracks 9 and 10. The magazine as shown are relatively superposed and they are inclined in a forward and downward direction, and the tracks 9 and 10 are preferably parallel to a line connecting the forward lower corners of the magazines, and the tracks 9 and 10 are also preferably inclined downwardly in a rearward direction. The lower ends of the magazines carry escapements 5^a, 6^a and 7^a respectively, the escapements of each magazine, when it occupies its operative position, being located immediately above and in position to be actuated by the respective reeds 4.

The upper track 9 at each side of the magazine unit rests on a roller 11 which may be composed of a roller or ball bearing of conventional type the outer race of which engages the lower edge of the track, and these rollers or the inner races of the bearings comprising them being supported by short shafts 12 which are fixed in the rear portions of the stationary main frame, the track 9 being thus

arranged to ride in a forward or rearward direction on these rollers, the track 9 being so located with respect to the center of mass of the magazine unit as to insure a preponderance of weight at the forward end of the magazine stack to tip it downwardly at its forward end.

A stop 13 which may be formed as a downward extension of the rear end of each track 9 is adapted to come into engagement with the rear side of the respective roller 11 and thereby limit the forward movement of the magazine unit, and a stop 14 which may be formed as a downward extension of the forward end 15 of each track 9 is arranged to come into engagement with the forward face of each roller 11 when the magazine unit has reached the limit of its rearward shifting movement, the stops 13 and 14 being spaced in conformity with the range of forward and rearward shift of the magazine unit to accommodate the number of magazines used. The forward stops 14 are formed with curved or hooked shaped extensions 14^a which are adapted to partially encircle the rollers 11, when the magazine unit reaches its rearmost position, and these forward stops will then serve to support the magazine unit while it is tipped rearwardly about the shafts 12 of the rollers 30 to bring the magazines into rearwardly and downwardly inclined position for changing of one or more of the magazines in the magazine carrying frame.

The lower tracks 10 have surfaces 10^a arranged to ride on a pair of rollers 15 which may be composed of roller or ball bearings of conventional type located at the respective sides of the magazines adjacent to their lower forward ends, each track having a flange 40 10^b projecting downwardly below the respective surface 10^a and at its inner side to engage the inner side of the respective roller and to thus prevent relative lateral displacement of the tracks from the rollers in either direction. The rollers 15 are so mounted that they will be in a relatively lowered position when any one of the magazines occupies its operative position and are movable into a relatively elevated position to tip the forward ends of the magazines upwardly so that they will clear the keyboard reeds and adjacent parts on the main frame and will be free to shift in a forward or rearward direction.

As shown, the rollers 15 are journaled in 55 crank arms 17 which are fixed to a shaft 18, the latter being journaled in bearings 19 in the portion 1^a of the stationary main frame, these crank arms being fixed to the projecting ends of the shaft at opposite sides of the main frame portion 1^a. One of the crank arms has an operating handle 20 fixed to or formed as a part of it, this handle being thus fixed to the shaft 18, and said handle which extends downwardly at a side of the portion 1^a of the main frame is adapted to swing in

a forward or rearward direction. As shown in Fig. 2, when the handle 20 is in its forward position, the crank arms 17 will extend substantially rearwardly from the shaft 18 and they will be in a relatively lowered position, this being the normal position of the handle and rollers when the forward ends of the magazines are lowered and one of the magazines is in operative position, and when the handle 20 is swung into the position shown in Fig. 3, the rollers 15 will be slightly beyond a dead center position above the shaft 18 and they are elevated, the tracks 10 resting on the rollers 15 being correspondingly elevated so that the lower ends of the magazines will be tipped upwardly sufficiently high to clear the keyboard reeds 4 and adjacent parts of the machine when the magazine unit is shifted in a forward or rearward direction. The beyond-dead center position of the rollers 15 above the shaft 18 will enable the rollers 15 to support the weight of the forward end of the magazine unit, thus rendering it unnecessary for the operator to maintain a hold upon the handle 20 to support the forward ends of the magazines in raised position. The rigid connections of the crank arms 17 to the shaft 18 causes both rollers 15 to swing in unison when the handle 20 is operated, the forward end of the magazine unit being thus supported evenly at both sides.

The rollers 15 controlled by the handle 20 serve to elevate or tip upwardly the forward ends of the magazines so that they will clear the keyboard reeds preparatory to a forward or rearward shift of the magazine unit, and means is provided by the present invention for automatically swinging the channel entrance 3 into a position to clear the upper ends of the magazines concurrently with the upward tipping of the forward ends of the magazines. As shown, the channel 3 is mounted at its ends on pivots 21 in the upper portion of the main frame at opposite sides of the magazine unit, the pivots 21 being so located that the channel entrance will swing to and from a position between the distributor and the upper end of a magazine occupying the operative position.

A bracket 22 supports each end of the channel entrance on its respective pivot, and the bracket at one end of the channel entrance is pivotally connected by the pivot screw 23 to a link 24, the latter being pivotally connected to the handle 20 at the point 25 which is below the axis of the shaft 18 of the tipping means. By this arrangement, a swing of the handle 20 from the normal position shown in Fig. 2 to the rearward position shown in Fig. 3 will push the link 24 rearwardly and the latter acting on the channel entrance will swing the channel entrance from its normal operative position shown in Fig. 2 rearwardly and downwardly to the inoperative position shown in Fig. 3, the channel entrance being then free of the path of the upper ends of the magazines

as the latter are shifted forwardly or rearwardly, and when the handle 20 is swung forwardly or returned to the position shown in Fig. 2, the link 24 will pull the channel entrance back into its normal operative position 5 as shown in Fig. 2.

The channel entrance is thereby automatically swung out of its operative position when the forward ends of the magazines are tipped upwardly and it is automatically returned to operative position when the forward ends of the magazines are lowered. When the channel entrance is swung rearwardly and downwardly to inoperative position, its weight, 10 which is considerable, will act, through the link 24, to hold the rollers 15 in elevated position, thereby preventing accidental dropping of the forward end of the magazine unit during shifting thereof.

20 The handle or operating lever 26 is provided for effecting the forward and rearward shifting movements of the magazine unit, this handle being located adjacent to the magazine lifting and lowering handle 20 and approximately coaxially therewith and extending 25 downwardly at a side of the forward portion 1^a of the main frame so that both of these handles may be reached and manipulated with facility by the operator occupying his usual 30 seat in front of the keyboard. The handle 26 as shown is fixed to the end of a shaft 27 which is fitted rotatably and in the main frame portion 1^a below the shaft 18, the handle 26 being connected to or formed integrally with a lever 35 28 which extends upwardly from the shaft 27 and is pivotally connected by a rearwardly extending link 29 to the forward end of the upper track 9. A lever 28^a is preferably fixed to the opposite end of the shaft 27 and is connected by a link 29^a to the upper track at that side 40 of the magazine unit, the levers 28 and 28^a swinging in unison and thereby insuring even forward and rearward shifting motions of the magazine unit, the forward or rearward swing 45 of the handle 26 acting through the levers 28 and 28^a and the links 29 and 29^a to cause forward or rearward shifting movement of the magazine unit, the latter being shown in its foremost position by the full lines in Fig. 3 50 and shifted into an intermediate rearward position by the dotted lines in that figure.

Owing to the inclination of the tracks 9 and 10, the weight of the magazine unit will 55 tend to cause the unit to gravitate toward its rearmost position and will require lifting the weight of the magazine unit when the latter is shifted forward. However, a pair of compression springs 30 is provided, one toward each side of the magazine unit, one end of 60 each spring being arranged to bear against a part of the main stationary frame and the other end thereof bearing against an adjusting collar 31 which is threaded on or otherwise adjustable longitudinally on a rod 32 65 one end of which is guided for longitudinal

movement by a hole 33 formed in a portion of the main frame 1 and the other end of the rod being pivotally connected at 34 to a crank arm 35 which may be formed as parts of the hubs of the arms 28 and 28^a fixed on the shaft 27 and these crank arms project upwardly 70 from said shaft, each spring encircling its respective rod and being thereby supported and prevented from buckling. The expansive action of these springs will tend to push the magazine unit forwardly and the combined strength of these springs is preferably such that it counterbalances substantially the tendency of the magazine unit to gravitate rearwardly, the effort required to shift the magazine unit forwardly and rearwardly being thus made equal or approximately so, and the magazine unit being able to remain in different positions into which it is shifted. The adjustable collars enable the strength of these 80 two springs to be adjusted as desired.

In order to facilitate the magazine shifting operation and to yieldingly retain the magazine unit in any one of the different operative positions into which it may be 90 shifted, the under side of the track 9 at each side of the magazine unit is preferably provided with depressions or slight notches 9^a which preferably correspond in number to the number of magazines contained in the 95 unit and in location to the operative positions of the different magazines; and these depressions receive the tops of the respective rollers 11 when the magazine unit is shifted to the point where the respective magazine will be set to move into operative position 100 when the forward end of the unit is lowered. The flange 10^b of the track 10 is preferably provided with similarly located notches 10^c and each of the crank arms 17 carrying the 105 rollers 15 is provided with a tooth or projection 10^d which, when the forward end of the magazine unit is lowered, after the desired magazine has been brought into proper position, will engage in the notch 10^c corresponding 110 with that magazine, the depressions or notches 9^a facilitating the bringing of the different magazines into operative position by resisting slightly, further shifting movement and thus informing the operator that 115 one of the magazines is in such position that when lowered, the respective notches 10^c will register with the teeth 10^d and such magazine will be brought into operative position, the notches 10^c and cooperating teeth 10^d 120 locking the magazine unit against displacement forwardly or rearwardly from operative position, after the forward end of the magazine unit has been lowered to bring the related magazine into operative position, maintenance of the proper working relationship between the escapements on the magazines in use and the actuating rods being thus 125 insured. When the forward end of the magazine is in its lowered operative position, it 130

will be effectively supported by the locking teeth 10^a and the rollers 15 which will both engage the respective tracks as is shown in Fig. 2. The teeth 10^a will be swung downwardly and thus released from the notches 10^c when the handle 20 is swung in a direction to tip the forward end of the magazine unit upwardly, so that the tooth or projection 10^a will then not interfere with forward or rearward shifting movement of the magazine unit.

The mode of operation of the magazine shifting means constructed as hereinbefore described is as follows. In Fig. 2, the rear-most magazine is shown in operative position with respect to the distributor and channel entrance and the escapement actuating reeds. In order to shift the magazine unit to bring the middle magazine into operative position, it is only necessary first to swing the lever or handle 20 rearwardly from the position shown in Fig. 2 to that shown by the full lines in Fig. 3, this operation raising the rollers 15 and thereby tipping the forward ends of the magazines upwardly or into the position shown in Fig. 3, and simultaneously disengaging the teeth 10^a from the notches 10^c which they previously engaged, the lower ends of the magazines being then above and clear of the escapement actuating reeds and adjacent parts of the machine, this same operation of the lever or handle 20 acting through the link 24 to swing the channel entrance from the operative position shown in Fig. 2 to the inoperative position shown in Fig. 3 where the channel entrance will clear the upper ends of the magazines; to pull the handle or lever 26 forwardly thereby swinging the levers 28 and 28^a and the links 29 and 29^a connected to their upper ends rearwardly until the middle depression 9^a in each track 9 engages the top of its respective roller 11, thus setting the middle magazine in properly shifted position; and to pull the handle or lever 20 forwardly to restore it to its initial position, this operation lowering the rollers 15 and, in consequence, the forward ends of the magazine so that the escapements of the middle magazine come into working relationship with the keyboard reeds 4 and the teeth 10^a are simultaneously swung upwardly to engage in the respective middle notches 10^c and simultaneously the link 24 is pulled forwardly, returning the channel entrance 3 to its normal operative position between the distributor and the upper end of the magazine in use.

The weight of the forward end of the magazine unit will serve to retain it in lowered position so that it rests on the rollers 15 and the locking teeth 10^a and the escapements of the magazine in use will thus be maintained in operative relation with the keyboard reeds. The foremost magazine 65 may be brought into operative position by an

operation similar to that just described, and to change from the foremost magazine to one of the magazines in rear thereof, the operation will be the same except that the handle or lever 26 is shifted in the opposite direction to that first described. Any force acting to accidentally or inadvertently shift the magazine unit while its forward end is in lowered operative position will be resisted by the locking of the teeth or projections 10^a in the respective notches 10^c corresponding with the magazine which is in use.

Fig. 5 shows the magazine shifting means substantially as hereinbefore described, applied to a magazine unit which is somewhat differently mounted on the main frame of the machine, it omitting the upper track on the magazine unit, as previously described, and employing instead, a track 36 which forms a part of the main frame of the machine, one of these tracks being provided at each side of the magazine unit, these tracks being inclined rearwardly as shown, and the frame 37 of the magazine unit is adapted to carry a roller 38 at each side thereof to ride on top of the respective tracks 36. The links 29^a which shift the magazine unit forwardly or rearwardly on the tracks are similar to the links 29 previously described except that they are longer and are pivotally connected to the frame 37 of the magazine unit at 39, these links effecting the forward and rearward shifting movements by means operated by the handle 26 as hereinbefore described in connection with the other figures, and the forward end of the magazine unit being lifted and lowered and held in the different operative positions when lowered, by means similar to that already described in connection with the other figures.

The mode of operation of the structure shown in this figure is similar to that already described, except that the rollers 38 supporting the upper portion of the magazine unit will travel forwardly or rearwardly on the tracks 36 on the main frame, during the magazine shifting movements.

The magazine shifting mechanism provided by the present invention is relatively simple and inexpensive, it consisting simply of the approximately concentric shafts which are supported on the main frame of the machine and the connections which lift and lower and shift the magazine unit, the construction being readily applicable to machines already in use as well as to new machines, and the location and arrangement of the operating handles which lift and lower and shift the magazine unit are such that they are within easy reach of the operator occupying his seat in front of the keyboard, and these handles may be easily swung forwardly and rearwardly by the operator without requiring him to leave his seat.

The substantially straight line shifting 130

movement of the magazine unit minimizes the effort required to shift the unit forwardly and rearwardly, and the counterbalancing springs overcome any tendency of the magazine unit to slide rearwardly under its weight when inclined tracks are used, and the springs, moreover assist the forward movement of the magazine unit, the strength of the springs being preferably such that the magazine unit may be shifted either forwardly or rearwardly with approximately the same effort applied to the shifting handle or lever.

I claim as my invention:—

1. In a typographical machine, the combination of a multiple magazine unit shiftable in a direction forwardly and rearwardly of the machine to bring one or another of the magazines thereon into operative position, and means for lifting the lower end of said unit and for maintaining it in elevated position during such shifting movement.

2. In a typographical machine, the combination of a multiple magazine unit, a track for guiding the forward end of said unit for shifting movement in a direction forward and rearward of the machine, and means for lifting said track and for maintaining it in elevated position during such shifting movement.

3. In a typographical machine, the combination of a main frame having escapement actuating means thereon, a magazine unit shiftable in a direction forwardly and rearwardly with respect to the main frame and carrying a plurality of magazines having matrix controlling escapements at their lower ends, a track arranged adjacent to the lower ends of the magazine and extending substantially in the direction of shift of said units, and means for elevating said track and thereby lifting the lower ends of the magazine and supporting them to shift in a path above the escapement actuating means on the main frame.

4. In a typographical machine, the combination of a main frame having escapement actuating means thereon, a multiple magazine unit shiftable relatively to the main frame in a direction forwardly and rearwardly thereof, a track connected to the magazine unit and extending in the direction of shifting movement thereof, and means cooperative with said track for lifting it and thereby supporting the lower ends of the magazines for shifting movement in a path above the escapement actuating means.

5. In a typographical machine, the combination of a main frame having escapement actuating means thereon, a multiple magazine unit shiftable in a direction forwardly and rearwardly relatively thereto, a track attached to the magazine unit and extending in the direction of shifting movement thereof, and a roller on the main frame cooperative with

said track to support it, said roller having means for raising it relatively to the main frame and thereby support the lower ends of the magazines for shifting movement in a path above the escapement actuating means.

6. In a typographical machine, the combination of a main frame, a multiple magazine unit shiftable in a direction forwardly and rearwardly relatively to the main frame and adapted to rest at its lower end thereon, tracks attached to the magazine unit at opposite sides thereof and extending in the direction of the shifting movement thereof, a shaft rotatably mounted in the main frame, and crank arms fixed to said shaft and carrying rollers so to cooperate with the respective tracks, rotation of said shaft operating to elevate said tracks and the lower end of the magazine unit.

7. In a typographical machine, the combination of a main frame, a magazine unit shiftable in a direction forwardly and rearwardly thereof, upper and lower tracks connected to the magazine unit, and means on the frame cooperative with said tracks for shiftably supporting said unit, said means for the lower track being capable of being raised to support the lower end of the magazine unit for shifting movement in a relatively elevated path.

8. In a typographical machine, the combination of a main frame, a magazine unit shiftable therein, a channel entrance movable into and out of operative relation with a magazine on said unit, means for setting the magazine unit in position to be shifted, and means operatively connecting the latter means to the channel entrance for automatically moving the channel entrance into inoperative position concurrently with the setting of the magazine for shifting movement.

9. In a typographical machine, the combination of a main frame, a magazine unit shiftable thereon in a forward and rearward direction, a channel entrance movable into and out of operative relation with a magazine on said unit, means for lifting the lower end of said unit to clear said frame, and means connected to operate concurrently with said lifting means to move the channel entrance into inoperative position.

10. In a typographical machine, the combination of a main frame, a magazine unit shiftable forwardly and rearwardly thereof, means for lifting the lower end of said unit relatively to said frame and for maintaining it in lifted position, means for shifting the unit while its lower end is maintained in lifted position, said lifting means and shifting means including adjacently located operating levers.

11. In a typographical machine, the combination of a main frame, a multiple magazine unit shiftable forwardly and rearwardly thereof to bring one or another of its magazines into operative position, means for lifting the lower end of said unit relatively to the

frame and for maintaining said end of the magazine unit in lifted position whereby it may shift forwardly or rearwardly in a path above said frame, and means operative, when 5 said lifting means is operated to lower said end of the unit, to engage said unit and retain it in operative position.

12. In a typographical machine, the combination of a main frame, a multiple magazine 10 unit having forwardly and rearwardly extending inclined tracks for shiftably supporting it on said frame, supporting rollers cooperative with said tracks, and means substantially counterbalancing the effect of the 15 weight of said unit on said inclined tracks.

In testimony whereof I have hereunto set my hand.

SAMUEL E. SPERRY.
